Samuel B. H. Vance New York.

Design for a Wall Pendant

Patented January 1st 1850.

Sam'l B. H. Vance, of New York, N.Y.

Nov. 753

Assignee

Mitchell Bailey, & Co. of State of Connecticut
Letters Patent No. 753. Date Jan. 1st 1853.

The schedule referred to in these Letters Patent and making part of the same.

To all whom it may concern.

Be it known that I, Samuel B. H. Vance, of the City, County, and State of New York, have invented an ornamental fixture, which is intended for a Hall Pendant; the configuration of which, and the grouping and combination of the several ornaments thereon, constitute a new and original design, and I do hereby declare that the following is a full and exact description thereof, reference being had to the accompanying drawings and to the letters of reference marked thereon, which make a part of this specification.

My fixture is so constructed as to be easily adapted to the use of gas, oil or any other illuminating material.

Fig. 1. In the drawings shows the pendant complete, except some of the ornaments upon the middle tubing rods.

Fig. 2. is the under side of the bottom of the pendant.

Fig. 3. is a distinct view of one of the ornaments upon the tubing rods.

On fig. 1. at the top is seen an ornamented helmet a, which is surrounded by branches with leaves b, this with two other similar ornaments surround the socket by which the pendant is suspended, and all are affixed to a bell shaped cup c. Immediately below the cup c is a large ornamented mace head B, within which the tubing rods D,D,D, terminate at the top. To this mace head chains e,e are attached ornamenteally and by them are suspended alternately with the tubing rods, three smaller ornamented

mace heads. —

About midway down the tubing rods and attached to each, are antique implements of war E.E.E. being a child with heraldic ornaments, a battle axe, a mace, grouped together, and appear suspended by a band and rosette (see also fig: 3.)

The three tubing rods unite at the bottom, and immediately under each of them is an ornamental group of emblem L. L. consisting of cuirass with designs upon it, spear, battle axe and, and with these are interwoven branches with leaves and flowers, better known in Fig: 2. Below the emblem L. L. and upon the bottom of the pendant is a triangular ornament with lion heads g. g. (see fig 2.) Alternating with these are three shields b. (see fig: 2. b, b, b.) In the center and at the bottom perpendicularly thereto is a turned ornament which is used as a key to let on or shut off the gas. —

What I claim as my invention and desire to secure by letter patent is the configuration and arrangement of the several parts and ornaments combined substantially as herein set forth and forming a new and original design for a Wall Pendant. —
